(57) **CLAIM**

The ornamental design for a gas filling machine main body as shown and described.

DESCRIPTION

FIG. 1 is a front elevational view of the gas filling machine main body of the present invention showing our new design; FIG. 2 is a rear elevational view thereof; FIG. 3 is a top plan view thereof; FIG. 4 is a bottom plan view thereof;

FIG. 5 is top, front perspective view thereof, and, FIG. 6 is a right-side elevational view, the left-side elevational view being a mirror image of the right-side elevational view.

The portions of FIGS. 1, 4 and 5 shown in broken lines do not form any part of the claimed design.

1 Claim, 4 Drawing Sheets
